Patented Sept. 16, 1924.

UNITED STATES PATENT OFFICE.

RICHARD STANDRING, OF ACCRINGTON, ENGLAND.

SHUTTLE FOR LOOMS FOR WEAVING.

Application filed October 2, 1923. Serial No. 666,117.

To all whom it may concern:

Be it known that I, RICHARD STANDRING, a British subject, residing at Accrington, county of Lancaster, England, have invented certain new and useful Improvements in Shuttles for Looms for Weaving, of which the following is a specification.

This invention relates to loom shuttles constructed with a metal threading device or block inserted in the head by which the shuttle can be readily and easily threaded by hand without drawing the yarn through the eye by any form of suction such as described in my former British Patent No. 128,869 of 1919.

The invention consists of a threading device or block made in two parts one part comprising a guide plate on top to fill the gap in the shuttle head under which the 20 yarn is passed and a downward projecting member forming a slot to receive the thread and prevent it unthreading and the other part comprising a curl to form the shuttle eye into which the yarn is directed to be 25 taken hold of by the finger of the operative.

It will be fully described with reference to the accompanying drawings.

Fig. 1. Plan of shuttle head showing the threading device in position.

Fig. 2. Sectional plan through the shuttle head and through the threading device.

Fig. 3. Longitudinal section through the shuttle head with side elevation of the threading device in position.

Fig. 4. Longitudinal section through the shuttle head showing the threading device in elevation from the opposite side.

Fig. 5. Side elevation of the shuttle head showing the aperture therein and the position of the curl eye.

Fig. 6. Transverse section through the shuttle head with end elevation of the threading device in position.

Fig. 7. Transverse section on line 7-7

Fig. 3.

Figs. 8 and 9. Perspective views from opposite sides of the part A of the threading device.

Fig. 10. Perspective view of the other 50 part B of the threading device.

The threading device is made in two parts A and B which are secured together in the

head of the shuttle C the part A forming a guide for the yarn and the part B forming the shuttle eye through which the yarn is drawn.

The part A is formed with a shank *a* by which it is secured to the shuttle, a top guide plate *a'* of curved or D shape to fill the gap in the shuttle head and direct the 60 yarn down into the interior, a side member *a''* turned inwards with a hook at the bottom end projecting downward from the guide plate *a'* to form a side passage *a'''* for the 65 yarn and a slot *a''''* cut in the back of the shank *a* to direct the yarn to the shuttle eye.

The part B is formed with a shank *b* by which it is secured to the shuttle and a curl eye *b'* with an extended guide member *b''* 70 which receives the yarn from the slot *a''''* and guides it into the centre of the eye.

The two parts A and B are together placed in the gap in the shuttle head and the shanks *a* and *b* are placed together and 75 fitted tightly into a slot cut in the bottom of the shuttle and are secured rigidly in position by pins *c* driven transversely through the shuttle C.

The shuttle is threaded by passing the 80 yarn round the underside of the top guide plate *a'* under the side member *a''* and through the side passages *a'''* and slot *a''''* into the curl eye *b* the side member *a''* preventing any unthreading of the yarn. 85

What I claim as my invention and desire to protect by Letters Patent is:—

The combination with a loom shuttle of a threading device formed in two parts, one part comprising a shank, top guide plate, 90 and downwardly depending side member turned inward with a hook at the bottom end which form passages for the yarn and the other part comprising a curl eye into which the yarn is directed and pins mounted 95 transversely through the two parts to retain them rigidly in position.

In testimony whereof I have hereunto set my hand in presence of two subscribing witnesses.

RICHARD STANDRING.
